UNITED STATES PATENT OFFICE.

FRANK HEMBES, OF CHICAGO, ILLINOIS.

FLY-ESCAPE FOR SCREENS.

1,260,261.

Specification of Letters Patent. Patented Mar. 19, 1918.

Application filed December 16, 1916. Serial No. 137,377.

To all whom it may concern:

Be it known that I, FRANK HEMBES, a citizen of the United States, and a resident of the city of Chicago, in the county of Cook 5 and State of Illinois, have invented certain new and useful Improvements in Fly-Escapes for Screens; and I do hereby declare that the following is a full, clear, and exact description of the same, reference being had to the accompanying drawings, and 10 to the numerals of reference marked thereon, which form a part of this specification.

This invention relates to an improved form of door or window screen wherein the 15 upper rail of the frame has a metallic casing disposed below the inner face thereof to afford a dark chamber adaptable as a fly trap and having a front portion provided with openings permitting flies or other insects to escape from the inside of the screen 20 through the casing and out through a suitable opening provided between the upper edge of the screening and the openings in the casing, the construction of the screen and 25 casing effectively preventing the entrance of flies or other insects through said openings into a room equipped with window screens of this type.

It is an object of this invention to construct a means attachable to a window screen to permit the escape of flies and other insects from a room, and effectively preventing the entrance of the same into the room.

It is also an object of this invention to 35 construct a window screen adapted to permit the exit of flies from a room and prevent the entrance thereof.

It is finally an object of this invention to provide an adjustable device for use on 40 fly screens of various sizes, simple and inexpensive of construction adapted to be readily attached in place to serve as a fly trap and also adapted to permit the escape of flies from a room without permitting the entrance of the same into the room.

The invention (in a preferred form) is illustrated in the drawings and hereinafter more fully described.

In the drawings:—

50 Figure 1 is a perspective vertical sectional view through a window screen equipped with a device embodying the principles of my invention.

Fig. 2 is a longitudinal section taken on line 2—2 of Fig. 1, showing both sections

of the device in telescopic relation with one another fitted into the screen frame.

Fig. 3 is a fragmentary front plan view of the device unmounted.

Fig. 4 is a slightly enlarged vertical section taken on line 4—4 of Fig. 3, showing parts of the screen frame.

Fig. 5 is a sectional view taken on line 5—5 of Fig. 2.

As shown in the drawings:

The invention comprises an adjustable casing or tubing consisting of two telescoping sections, denoted as a whole by the reference numerals 1 and 2, as clearly shown in Fig. 2, and adapted by adjustment to fit 70 into window screen frames of different sizes.

As shown in the drawings, a screen frame, comprising a bottom rail 3, a top rail 4, and stiles 5, connecting said rails 3 and 4, has attached thereto by any suitable means a wire 75 screening 6, the upper edge of which extends to within a short distance of the upper rail 4, providing an opening as shown in Fig. 1, for a purpose hereinafter described.

The casing section 1, is made of metal 80 or other suitable material bent or formed to afford a right angled channel portion comprising a back or base 7, an upper side 8, and a lower side 9. Bent upwardly at right angles to the upper side 8, and then 85 downwardly upon itself is an integral flange or front piece 10, having an integral wing or flap 11, at the outer end thereof. Cut or stamped from the lower portion of the front piece 10, are a plurality of equidistantly 90 spaced tongues 12, bent inwardly at right angles to lie flat against the upper channel side 8, and then bent downwardly parallel to the channel back 7, and to the wire screening 6, and disposed behind the opening afforded between the upper edge of said wire screening and the lower edge of the top rail 4. The tongues 12, thus stamped and bent rearwardly afford a plurality of rectangular openings 13, separated from one 100 another by parallel strips or slats 14, and each having struck outwardly therefrom downwardly directed clips or fasteners 15, adapted to engage over the upper edge of the wire screening 6, and lie flat against the 105 front surface thereof to rigidly hold the same in position. The forward or front edge of the lower channel side 9, is cut or stamped to afford a plurality of openings 16, registering with the openings 13, and sepa-

rated by nubs or fingers 17, which contact the lower ends of the strips 14, and may be soldered or secured thereto by other suitable means if desired. To permit attachment of 5 the casing section 1, to the upper rail 4, and the right hand stile 5, apertures 18, are provided in the front piece 10, and in the flap 11, to receive nails or screws 19.

The construction of the casing section 2, 10 is identical with that of the sections 1, except that it is a left hand section and slightly smaller to permit the same to be telescoped into the section 1, to fit into the screen frame, after which the sections are rigidly 15 fastened in position.

The operation is as follows:

The window screen, on which it is desired to mount the telescoping sections 1 and 2, 20 is first arranged to have the wire screening 6, cut or lowered so that its upper edge extends to within a short distance of the lower front edge of the upper rail 4. The section 2, is then telescoped into the section 1, until the length of the casing is such that it will 25 fit between the stiles 5, with the upper channel sides 8, contacting the lower surface of the upper rail 4, and with the rear surfaces of the front pieces 10, and the flaps 11, engaged against the front surfaces of the upper rail 4, and the stiles 5, as clearly shown 30 in Fig. 1. The clips 15, are then engaged over the upper edge of the screening 6, and bent downwardly against the front surface thereof, and the casing and screening is 35 then securely fastened in position by means of the screws 19, which engage through the apertures 18, provided for the purpose.

With the casing and the wire screening in 40 position as described and as shown in Fig. 1, an escape is provided for flies which may travel upwardly through the openings 16, into the front portion of the channel chambers 7—8—9, of the sections 1 and 2. The rear portions of the channel chambers, however, being darkened by the tongues 12, and 45 the strips 14, serve as a trap for flies which find their way therein, while other flies in the forward portion of the channel chambers seeking the light and on account of 50 their habit of moving upwardly continue on their way passing through the rectangular openings 13, to the outside of the window screen through the opening afforded between the upper edge of the wire screening 6, and the upper edge of the framing forming 55 the openings 13.

While the device in combination with the window screen as described, serves as a trap and also affords an escape for flies from a 60 room in which the window screen is used,

it also acts effectively to prevent the entrance of flies into the room, due to the fact that the chambers afforded by the sections 1 and 2, are darkened by the tongues 12 and 65 the strips 14, and since flies do not travel downwardly into dark spaces, they will not try to enter the room over the upper edge of the screening 6, through the openings 13 and 16.

It will, of course, be understood that the 70 casing may be made of but a single section to fit within a window screen of a certain size, or that the device may be made of a center section constructed similar to that described, but having telescoping end pieces 75 to permit adjustability for fitting the device to window screens of different sizes.

I am aware that various other details of construction may be varied through a wide 80 range without departing from the principles of this invention, and I therefore do not purpose limiting the patent granted otherwise than necessitated by the prior art.

I claim as my invention:

1. The combination with a screen frame, 85 of a wire screening secured thereto and having its upper edge extending to within a short distance of the upper portion of the frame to afford an opening, telescoping chambered sections secured in said frame 90 behind said opening, means struck inwardly from said sections to darken said chambers and afford a series of openings therein, strips separating said openings, and means struck outwardly from said strips adapted 95 to engage over the upper edge of said wire screening, said openings affording a means for the escape of flies from behind the wire screening, and said darkened chambers serving as a trap for flies and also tending to 100 effectively prevent the entrance of flies through said openings.

2. In a device of the class described the combination with a window screen frame having its screening extending to within a 105 short distance of the upper rail thereof, of adjustable telescoping means having openings therein secured in said frame behind the upper end of said screening to permit the escape of flies from behind said screening through said openings and out over the upper edge of said screening.

In testimony whereof I have hereunto subscribed my name in the presence of two subscribing witnesses.

FRANK HEMBES.
